US00D800331S

(12) **United States Design Patent** (10) **Patent No.:** **US D800,331 S**
(45) **Date of Patent:** **** Oct. 17, 2017**

(54) **MOLECULAR DIAGNOSTIC DEVICE**(71) Applicant: **Click Diagnostics, Inc.**, Menlo Park, CA (US)(72) Inventors: **Colin Kelly**, San Francisco, CA (US); **Victor Briones**, Gilroy, CA (US)(73) Assignee: **Click Diagnostics, Inc.**, San Jose, CA (US)(**) Term: **15 Years**(21) Appl. No.: **29/569,628**(22) Filed: **Jun. 29, 2016**(51) LOC (10) Cl. **24-01**

(52) U.S. Cl.

CLAIM

The ornamental design for a molecular diagnostic device, as shown and described.

DESCRIPTION

FIG. 1 is a top perspective view of the molecular diagnostic device;

FIG. 2 is a bottom perspective view of the molecular diagnostic device illustrated in FIG. 1;

FIG. 3 is a top view of the molecular diagnostic device illustrated in FIG. 1;

FIG. 4 is a bottom view of the molecular diagnostic device illustrated in FIG. 1;

FIG. 5 is a left side view of the molecular diagnostic device illustrated in FIG. 1;

FIG. 6 is a right side view of the molecular diagnostic device illustrated in FIG. 1;

FIG. 7 is a rear view of the molecular diagnostic device illustrated in FIG. 1;

FIG. 8 is a front view of the molecular diagnostic device illustrated in FIG. 1;

FIG. 9 is a top perspective view of the molecular diagnostic device in FIG. 1, including a region 10;

FIG. 10 is an enlarged top perspective view of the molecular diagnostic device illustrated in FIG. 1, the enlarged region being identified by the region 10 in FIG. 9, and showing a first actuator of the molecular diagnostic device;

FIG. 11 is a top perspective view of the molecular diagnostic device in FIG. 1, including a region 12;

FIG. 12 is an enlarged top perspective view of the molecular diagnostic device illustrated in FIG. 1, the enlarged region being identified by the region 12 in FIG. 11, and showing a second actuator of the molecular diagnostic device;

FIG. 13 is a top perspective view of the molecular diagnostic device in FIG. 1, including a region 14;

FIG. 14 is an enlarged top perspective view of the molecular diagnostic device illustrated in FIG. 1, the enlarged region being identified by the region 14 in FIG. 13, and showing a third actuator of the molecular diagnostic device;

FIG. 15 is a top perspective view of the molecular diagnostic device in FIG. 1, including a region 16;

FIG. 16 is an enlarged top perspective view of the molecular diagnostic device illustrated in FIG. 1, the enlarged region being identified by the region 16 in FIG. 15, and showing three status indicators of the molecular diagnostic device;

FIG. 17 is a top perspective view of the molecular diagnostic device in FIG. 1, including a region 18; and,

FIG. 18 is an enlarged top perspective view of the molecular diagnostic device illustrated in FIG. 1, the enlarged region being identified by the region 18 in FIG. 17, and showing the detection windows of the molecular diagnostic device.

In the drawings, the dashed lines (--) depict portions of the article that form no part of the claimed design. The chain lines (---) represent the bounds of the claimed design. The boundary illustrated by the chain lines does not exist in reality in the article embodying the design.
